METHOD OF MAKING A HEAT EXCHANGE ELEMENT

Alfred J. Berg, Portsmouth, N. H., and John O. Huse, United States Navy

Application August 4, 1937, Serial No. 157,378

7 Claims. (Cl. 29—157.3)

(Granted under the act of March 3, 1883, as amended April 30, 1928; 370 O. G. 757)

Our present invention relates to a new and useful heat or cold exchanging element and method of making the same, which element may be otherwise usefully employed.

This invention is a continuation in part of and an improvement upon our application, Serial No. 63,894, series of 1935, entitled "Heat exchanging element and process of making the same", filed February 14, 1936. In said filed application the 10 ribs or fins of heat exchanging elements were machined or cut as a shaving from a bar of metal. Our present invention substantially improves the helical shaving cut from a bar of metal having a central longitudinal hole therethrough and adapted to form the rib or fin of a heat exchanging element which may be hollow. Our present invention furthermore substantially improves the cutter by which such shaving may be formed.

The objects of our invention are to improve 20 the strength and stability of the shaved rib or fin; to avoid the liability of breaking the shaved fin as it passes over the thicker part of the cutter immediately after it is severed from the bar of metal, as well as to avoid the liability of breaking 25 the fin while it is being installed upon and secured to its tube and/or in handling the finished tube; also to provide an improved cutting tool for more efficiently and economically shaving such improved fin from a bar of metal and which cutter will maintain its edge for protracted periods without stopping the machine and resharpening the 30 same or liability of breaking the rib or fin formed by said cutting tool. Other objects of the invention will hereinafter be made apparent.

In the drawing illustrating our invention, Fig. 1 is a top plan view of a cutter for lathes and the like for cutting our improved heat exchanger rib or fin from a bar of metal;

Fig. 1a is an end view thereof;

Fig. 1b is a side elevation view of the cutter shown in Fig. 1;

Fig. 1c is a view of a cutting tool similar to Figs. 1 and 1b but having a different shearing cutting edge;

Fig. 1d is a view in side elevation of a further embodiment of the cutter;

Fig. 1e is a view in end elevation of this embodiment; and

Fig. 1f is a view in plan thereof.

Fig. 2 is a top plan view of a bar of metal with the cutter of Fig. 1 cutting a helical shaving from the end face thereof to form a helical rib for a heat exchanger tube.

Fig. 2a is a view showing a preferred relation 55 of the shearing edge to the bar.

Fig. 3 is an end view of a bar of metal mounted for rotation in the chuck of a lathe or like tool with the cutter of Fig. 1b positioned to cut a shaving from the end face of such bar adapted to form a rib or fin for a heat exchanger tube. 5

Fig. 4 is a view similar to Fig. 3 but employing the cutter illustrated in Fig. 1d;

Fig. 5 is a cross-sectional end view of a portion of the shaving adapted to form the rib or fin of a heat exchanger tube, the section being taken upon 10 a plane passing through the center and one side of the helically turned shaving.

Fig. 6 is a central vertical cross-sectional view of a portion of a heat exchanger tube or element provided with ribs or fins formed of the shaving 15 11b.

10 diagrammatically represents the chuck of a lathe or like tool adapted to rigidly hold a relatively long bar 11 of metal concentric with spindle 12, Fig. 2, of the lathe or like tool. 13 represents a portion of the usual lathe carriage to which tool post 14 is rigidly attached. Post 14 is usually bifurcated to receive the shank of cutting tool 15 which is secured in said bifurcation by screw 16. The cutting edge 17 of the cutting tool 20 15 extends across the end of bar 11 from a point within the central longitudinal opening 11a extending through bar 11 to a point beyond the diameter of bar 11 so as to cut a shaving of the 25 required thickness from the end of bar 11 as the same is turned in the lathe while the carriage 13 is progressively moved by the usual feed screw, not shown, to progressively move the cutting edge longitudinally of the bar 11. It is such longitudinal movement of the cutting edge 17 relative 30 to the rotation of bar 11 that fixes and maintains the thickness of the shaving severed from the bar 11 which forms the helical fin of a heat 35 exchanger tube or element.

When using a cutting tool having a straight 40 cutting edge to sever the shaving 11b from bar 11 we have found that the shaving is liable to break as it is being severed and simultaneously bent at the wide angle necessary for it to pass over the bevelled portion of the cutting tool 15 which supports its cutting edge 17. This we have found is due to a number of factors, including the cold worked forming of bar 11 with the resulting grain distortion of the metal of bar 11, together with the further grain distortion due to the cutting 45 of the shaving 11b. Such breakage is contributed to by the line of breakage usually being radial relative to bar 11 and that such line coincides with the straight cutting edge of the tool so that the severance and simultaneous bending of the 50 55

shaving occurs in such radial line extending throughout the width of the shaving.

Our present invention provides means for the overcoming of this difficulty whose liability of occurrence increases with the thinness of the shaving which thinness is most desirable and advantageous for many purposes including lightness of weight, cost, greater efficiency and capacity for heat exchange, greater rapidity of and economy of production and superior excellence and appearance of the finished product. Said provided means include the following: Normalizing or annealing the metal of bar 11 is one such remedy, but it adds to the time and expense required for such operation. For more economical and efficient results we prefer to form bar 11 by extruding hot metal to the required length through a die forming the required external and internal diameter and then normalizing by reducing to atmospheric temperature the hot drawn metal of bar 11.

We further provide a cutting tool having its cutting edge disposed otherwise than upon a straight line extending substantially radially relative to bar 11, and preferably upon an un-uniform or generated line which will form a shearing cutting edge which is disposed at an angle, or at a varying angle relative to a radial line passing through the bar 11.

30 A further provision tending to avoid such difficulty is that the shaving 11b is formed more or less cambered, as shown in Fig. 5, that is of uniform thickness thereof curved with the high point of the curve occurring in the center or at 35 a point intermediate the width of the shaving. Such cambered shaving affords additional initial strength to the severed shaving and necessitates no waste of the metal of bar 11.

40 The different cutting tools 15 which we have provided for the severance of our improved shaving 11b, which is essentially adapted to form a helical heat exchanger rib or ribs upon a heat exchanging tube or element will now be described.

The tool shown in Figs. 1b, 1c, and 3 has its cutting edge 17, as will more clearly appear in Fig. 3, disposed at an angle to a line which is radial relative to bar 11. The point of the tool of the cutting edge 17 extends within the bore 11a of bar 11 and terminates outside of the diameter of bar 11 and near the highest point of such cutting edge, relative to the light radial line shown in Fig. 3. Such highest point of cutting edge 17 is in the instance shown in Fig. 3 near the outer diameter of bar 11. One advantage of such disposition of cutting edge 17 is that its greatest shearing action upon the metal of bar 11 occurs in the smaller diameter portion of bar 11 where the relative cutting speeds are substantially less than the relative cutting speeds of the metal in the larger diametered portions of bar 11. This form of shearing cut, shown in Figs. 1b and 3, have been found effective and efficient as well as to obviate the liability of the breakage of the shaving hereinbefore described.

65 The cutting edge 17a of the cutting tool 15 shown in Figs. 1d and 4, provides a different shearing action upon the metal of the bar 11 than disclosed by the cutting edge 17b in Figs. 1 and 3. The cutting edge 17a shown in Figs. 1d and 4 has its highest point at 17x or adjacent the center of the width of the shaving 11b. From this high point the cutting edge 17a progressively lowers as it extends in opposite directions from said high point. The high point of the cutting edge 17a may be the apex of angular

oppositely extending straight portions of the cutting edge 17a, but in the instance shown in the drawing said cutting edge is curved. The high point of cutting edge 17a being at a point intermediate the sides of the shaving 11b tends to obviate all, or at least the major portion, of the end thrust upon the cutter 15 as well as the resulting lateral thrust upon the bar 11 from which the cutting edge shaves the shaving 11b. This avoidance of thrust is due to the high point 10 of the cutting edge 17a being at a point within the thickness of the shaving 11b and the oppositely curved portions of the cutting edge 17a substantially neutralize any end thrust on cutter 15 as well as lateral thrust upon the bar 11. 15 Further than this, the central portion of the shaving 11b is severed from the end of bar 11 while the opposite sides of the shaving 11b are still an integral part of the bar 11. These unsevered lateral portions of shaving 11b are severed by the cutting edge 17a while its high point 20 is continuing its advanced severance of the central portion of the width of the shaving 11b. This shearing cut of the shaving 11b afforded by this cutting edge 17a furthermore results in the 25 forming of substantially the cambered shaving 11b shown in Fig. 5, due to the fact that the high point of the cutting edge 17a severs the central portion of the shaving 11b from the end of bar 11 and forces the same progressively over 30 the thicker bevelled portion of the cutter 15 upon the upper edge of which the cutting edge 17a is formed. This severance in forcing over the central bevelled portion of cutter 15 of the central portion of the severed shaving 11b while its lateral edges are still integral with the bar 11 causes 35 the central portion of the shaving 11b to be curved outwardly, and such curvature progressively lessens as the lateral edges of the shaving 11b are approached. This is true because a radial 40 line passing from the center of the bar 11 through the points of intersection of the inner and outer diameters of the bar 11 with the cutting edge 17a will also pass through progressively thicker 45 portions of the bevelled edge of cutter 15 whose apex forms the cutting edge 17a. Such progressively thicker portions will be passed through by said radial line until the high point of the cutting edge 17a is reached, and from this point to the outer diameter of bar 11 this radial line will pass 50 through progressively thinner portions of the cutter 15. It is these progressively thicker and then thinner portions of the cutter 15 over which the shaving is passed as it is being sheared from 55 bar 11 that results in such camber of shaving 11b as is substantially indicated in Fig. 5.

To enable a straight cutting edge of a cutter 15, or even the cutter of Figs. 1b and 3 to cut a cambered shaving 11b, substantially as shown in Fig. 5, from the bar 11 a transversely arched cutting 60 edge 17b is formed at and beneath the actual cutting edge of the cutter 15. This arched cutting edge 17b severs the cambered shaving 11b directly from the bar 11.

The vertical surface 17c directly beneath each 65 of the several cutting edges 17, 17a and 17b extended at a downward and outward angle from their respective cutting edges so as to afford substantial clearance between the end of bar 11 and portions of the cutter 15 below the cutting edge of each of the cutters that may be employed in severing the shaving 11b from the bar 11.

It will be appreciated by those skilled in the art that the cambered shaving 11b affords greater 75

than normal strength to the shaving 11b, as well as contributes to the avoidance of the liability of the breakage of the shaving 11b, at any point in its length as the same is being severed and bent over the thicker portion of the cutter supporting the cutting edge which separates the shaving from the bar 11. It will furthermore be appreciated by those skilled in the art that the shearing cutting edges 17 or 17a substantially contribute to the severance of the shaving 11b from the bar 11 more efficiently and with less power; that said shear cutting edge or edges efficiently cut for longer periods than non-shearing cutting edges; that said shearing cutting edges substantially contribute to the avoidance of the breaking of even the thinner shavings 11b even of the un-normalized or un-annealed bar 11, and make a more efficient as well as stronger shaving from the normalized or extruded bar 11; that the longer service enduring shearing cutting edges 17, 17a, also require less stoppage of the shaving cutting for the purpose of sharpening or changing the cutter 15, which sharpening or change also necessitates a careful re-adjustment of the sharpened or replaced cutter 15 in order to continue without flaw precisely the path of the former cut in order to maintain the uniform thickness of this shaving 11b; that the shear cutting of the shaving 11b cold works the shaving by distorting one portion of the grain of the metal of the shaving 11b while an adjacent portion or portions of the grain of the metal of the shaving remains for the instance an integral portion or portions of the bar 11 and which contributes to the avoidance of the liability of the breakage of the shaving 11b in the plane of such grain of the metal of the shaving, and that such cold working increases the surface density as well as the heat exchanging capacity and efficiency of the shaving 11b; and that the cold working and other advantages of said shear cut are increased by the cutting as well as by the progressive forming while shaving the cambered shaving 11b from the bar 11.

In turning or cutting the shaving 11b helically from the end of the bar 11 the central opening 11a longitudinally through the center of bar 11 enables the helical shaving 11b to be formed with the central opening therethrough 11aa, Fig. 2, which substantially conforms to the external diameter of the heat or cold exchanging tube or body 20, Fig. 6. A suitable length of the helical shaving 11b may be placed about the tube or body 20 with one end of said shaving secured at a desirable point upon tube or body 20 by a drop of solder 21. The shaving 11b may be uniformly spaced throughout the length of tube or body 20 by pressure applied to the unsecured end of the shaving 11b which is then adapted to be secured to the tube or body 20 by another portion of solder 21 or other securing means and the shaving severed at the outer end of said last securing 21. The size of the bore 11a in bar 11 is such that the resulting diameter of central opening 11a in shaving 11b will be a snug fit upon and about the exterior surface of the tube or body 20 and afford a firm and efficient engagement of high thermal conductivity between the surface of tube or element 20 and the helical shaving 11b.

It will be understood by those skilled in the art that the helical shaving disclosed in Figs. 4 and 12 as well as 13, 14, 15 and 16 of the drawing of our application, Serial No. 63,897, series of 1935, entitled "Heat and cold exchanging element and method of making the same," filed February 14, 1936, may be made in accordance with our ap-

plication 63,894, series of 1935, entitled "Heat exchanging element and process of making the same", filed February 14, 1936.

It will be readily understood by all those skilled in this art from the foregoing as to the precise method of making the heat exchanger comprising the herein disclosed shaving employed as the rib or fin of such heat exchanging element, as well as the method of making the herein disclosed shaving together with the making of the bar from which the shaving is made; that the extrusion of the bar from which the shaving is made as well as the production of the shaving 11b may be performed by any one of a number of existing machines and that the final production of the ribbed or finned heat exchanging element may be done by hand or by a number of existing apparatus with or without substantial modification; that the practice of said method results in the more economical and efficient production of a thinner, wider, stronger, lighter, cheaper and more efficient heat exchanger element of greater capacity per unit of length and weight than has been heretofore commercially producible; that a heat exchanging rib or fin, either circular or helical for a heat exchanger tube or body of greater thinness, width and strength may be more cheaply and efficiently produced by our present method than has been heretofore possible of production from an unannealed or unextruded tubular bar of metal, and that when shaved as herein disclosed from such a normalized or extruded bar the shaving and its resulting fin or rib will be still stronger, lighter and more efficient as well as may be made wider; that by the prior practice of making heat exchanger ribs or fins from an edgewise bent flat strip of metal, the height of the rib or fin, represented by the width of the strip, could not approximately exceed one-half the diameter of the tube or body to be provided with such ribs or fins and that such height or width could be slightly increased by pre-coiling the strip to an intermediate diameter before finally coiling the same about the tube or body; that by the method disclosed in our said application No. 63,894, series of 1935, the height of the rib or fin represented by the width of the shaving could be substantially increased by shaving a helical shaving from the end of a tubular bar and employing such shaving as the rib or fin of the heat exchanger element; and that a substantially wider, thinner, stronger and more efficient shaving of greater strength and heat or cold exchanging capacity per unit of weight and length of substantially less liability of flexure may be formed of the generic as well as the specific shearing disclosed in our present application.

It will be understood by those skilled in this art that there are substantial problems in the making of heat exchanger ribs or fins from a shaving cut from one end of a tubular bar of metal, and that applicants have solved said problems in and by their present invention. The major one of said problems appears to be that the shaving when severed from the bar substantially upon a radial line passing through its axis of rotation compels the simultaneous severance and substantial lateral bending of the shaving along said radial line which is the shortest distance across the width of the shaving and hence the weakest point in such shaving. This liability of breakage of the shaving is overcome by the following contributory factors arising from applicants' present shearing line of cleavage of the

- shaving from the bar substantially departing from said radial line;
1. This shearing cleavage line increases in angularity as the cutting speed decreases toward the center of rotation of the bar from which the heat exchanger ribs are turned.
  2. While the metal toward the periphery of the bar is being sheared through a point in a radial line passing through the axis of rotation of the bar, some metal of the bar toward its center of rotation and extending beyond the cleavage line is below said radial line and still unsheared from the bar and supports the sheared part of the shaving from liability of breakage while being laterally bent over the outer side of the cutting tool.
  3. The shearing or cleavage line of the shaving from the bar is curved in the plane of rotation and substantially longer than a radial line extending through the axis of rotation of the bar. This renders the shaving wider and stronger along such curved line of cleavage which consequently increases the bendability of the shaving and substantially decreases the liability of breakage of the shaving while being bent laterally over the outer surface of the cutting tool.
  4. The angular line of cleavage of the shaving from the end of the bar of metal causes a flowage of metal along the line of cleavage as well as angularly across the cleaved surfaces. This results in a smoother, more burnished and cold worked shaving on each of its opposite cleaved surfaces which increases the stability, surface density and heat transfer properties of the shaving. This also reduces the liability of the accumulation of dust, sediment and other insulating mediums upon the surfaces of the shaving. The cutter illustrated in Fig. 3 affords a greater rate of such flowages to equalize the lesser cutting speed as the center of bar 11 is approached. The cutter illustrated in Fig. 4 at its inner end affords the same flowage equalizing advantages but increases the rate of flowage along the outer portion of the shaving to afford the highest degree of burnishing and cold worked characteristics toward the periphery of the fin where the maximum heat exchanging takes place and where the resistance to flow of the medium to be heated or cooled is greatest.
  5. The above stated flowage of metal may be better understood when characterized as being a deflection of very small portions of metal of the outer portions of the sheared surfaces. Such deflections occur in a direction at an angle to a radial line passing through the center of rotation of the tubular bar whose end is being shaved. Such direction, when the shearing edge lowers as it approaches the inner bore of the tubular bar occur at an inward angle, while when the shearing edge drops as it approaches the periphery such deflection occurs in an outward direction. At the high point of the shearing edge, whether such edge drops only in one or in two opposite directions, affords no angular deflection, in a sense, bends a small outer portion of the metal of the sheared surfaces at an angle and impinges the same frequently against the normal undeflected adjacent metal. Such deflected metal also impinges and, in a sense, interlocks with other portions of deflected metal as well as with portions of undeflected metal against which the same are impinged with the substantial force arising from the angular shearing. Such flowage or deflection may furthermore be better understood when characterized as something akin to

metal spinning in which a blunt tool deflects or flows metal from there to different points of the surface upon which it acts. In applicants' case, the relativity of the axis of rotation of the metal bar (from the end of which the shaving is sheared) and the shearing edge occasions the, in effect, spinning, deflection or flowage simultaneously with the shearing of the shaving from the end of the bar.

A preferred relativity of the shearing edge 17, 17a, or 17b, with the bar 11 is shown in Fig. 2a in which the inner tip of such cutting edge, which extends slightly within the bore 11a of tubular bar 11 is approximately $\frac{1}{32}$ " closer to the chuck or face plate 10 of the lathe than is the adjacent side of cutter 15 at approximately the center of the tool post 14. This forms a slightly dished end surface of the bar 11 as indicated in Fig. 2a. This also tends to produce a helical shaving which is slightly thinner at its periphery than at the inner edge of the central longitudinal opening therethrough.

A further preferred relativity of the shearing edge 17, 17a or 17b is that the high point 17x of the shearing surfaces shown in Figs. 3 and 4 is slightly above a horizontal line passing through the axis of rotation of the bar 11, while the other portions of such shearing edges drop toward and/or below said line as such shearing edge extends across the thickness of the wall of tubular bar 11. We have obtained very satisfactory results with said high point approximately $\frac{1}{32}$ " above such horizontal line.

The arched shearing edge 17b of cutting tool 15 of Fig. 1 also produces a correspondingly curved end wall of the tube 11, so that only the thinner small initial portion of the shaving is required to be broken off, which represents that initial portion until the shearing edge 17b helically attains the required thickness of the 40

In Figs. 2, 3 and 4, we provide a rod 11c which extends into opening 11a throughout the length of bar 11 and projects beyond the outer end of bar 11a to receive and hold concentric with bar 11 the helical shaving 11b as the same is cut from the end of said bar 11. This steadies the severed portions of the helices 11b and materially tends to prevent their being broken from the bar 11, as well as prevents the free end of the severed 50 helix 11b from being whipped about by the turning of the lathe to the menace of the operator.

The surface 11c extending downward from the cutting edge 17, 17a, 17b shapes away from said cutting edge about three degrees in order to afford clearance between said surface 11c and the unsevered end of bar 11.

The beveled surface, opposite surface 11c, extends downward from said cutting edge at a wide angle in order to afford substantial strength of metal supporting said cutting edge. As the severed portion of helix 11b flows over this beveled surface its surface in contact therewith is highly burnished while its opposite surface assumes a frosted appearance at the point where it bends sharply away from the unsevered metal comprising the end of bar 11. This frosted appearance extends uniformly, in many instances, throughout the outer surface of the severed portion of the helices 11b and seems to be occasioned by a compression of the metal comprising the outer surface of the helices 11b. The opposite surface of the severed portion of the helices 11b probably is formed by metal of such surface being stretched by the sharp angle at which the helices

11b are separated from the end of bar 11, and is certainly polished substantially by its sliding contact over the beveled surface of the cutting tool 15. Such cold working of the opposite major surfaces of the helices 11b increase the resistance to breakage as well as the capacity of said surfaces of the helices to transfer heat or cold. Such cold working also increases the thinness of said helices 11b and the heat or cold exchanging efficiency and lightness of the heat exchanger element 20 with which the same may be provided by increasing the number of such helices 11b per unit of length of element 20 without impairing the upright stability of the helices 11b by reason of their increased strength and greater freedom from breakage and deformation provided by said cold working.

This invention may be made and used by or for the Government of the United States for governmental purposes without the payment of any royalty thereon or therefor.

Having now so fully described our invention that others may therefrom make and use the same, what we claim is:

25 1. The method of making a helical fin of relatively wide, thin metal having a longitudinal opening through its center and the helix cambered in cross-section comprising separating from the end of a tubular bar of metal a central initial portion of the helix and stretching the same to form the camber, and then separating from the bar the inner and outer edges of the separated and stretched portion of the helix.

35 2. The method of making a helical fin of relatively wide, thin metal having a longitudinal opening through its center and the helix cambered in cross-section comprising separating from the end of a tubular bar of metal a central initial portion of the helix and stretching the same to form the camber, and then separating from the bar the inner and outer edges of the separated and stretched portion of the helix while a further advanced central portion of the helix is being severed from the bar and stretched, and

progressively continuing said operations until the desired length of helix is obtained.

3. The method of making a helical rib for a heat exchanging element having a longitudinal opening through its center and helices of wide, thin metal cambered in cross-section by shearing progressive portions of the helix from the end of a tubular bar of metal with the line of shear being of substantially the camber required in the helices.

10 4. The method of making a helical heat exchange fin comprising progressively cutting a bar of high heat conductivity metal continuously at its end along a non-radial line thereof and in the direction of its length to directly form by 15 the cutting operation a helical heat exchange fin.

5. The method of making a helical heat exchange fin comprising progressively cutting a bar of high heat conductivity metal continuously at its end and in the direction of its length to 20 directly form by the cutting operation a helical heat exchange fin, and concurrently with the aforesaid cutting operation imparting a camber to the helical heat exchange fin.

25 6. The method of making a helical heat exchange fin comprising progressively cutting a bar of high heat conductivity metal continuously at its end along a non-radial line thereof and in the direction of its length to directly form by the cutting operation a helical heat exchange 30 fin and concurrently with the aforesaid cutting operation imparting a camber to the helical heat exchange fin.

35 7. The method of making an apertured helical heat exchange fin comprising progressively cutting a longitudinally apertured bar of high heat conductivity metal continuously at its end and in the direction of its length to directly form by the cutting operation an apertured helical heat exchange fin and supporting the apertured helical heat exchange fin at its inner periphery during 40 the cutting operation.
